UNITED STATES PATENT OFFICE.

DAVID H. MOSS, OF BROOKLYN, NEW YORK, ASSIGNOR TO C. BRANDES, INC., OF NEW YORK, N. Y., A CORPORATION OF NEW YORK.

SUPPORT FOR TABLE TALKERS AND METHOD OF MAKING THE SAME.

Application filed February 9, 1924. Serial No. 691,812.

To all whom it may concern:

Be it known that I, DAVID H. Moss, a citizen of the United States, residing at Brooklyn, in the county of Kings and State of New York, have invented a certain new and useful Improvement in a Support for Table Talkers and Methods of Making the Same, of which the following is a specification.

My invention relates broadly to electromagnetic sound reproducers, and more particularly to the construction of a support and an assembly for such electromagnetic sound reproducers, and the method of making such support and assembly.

One of the objects of my invention is to provide a support for an electromagnetic sound reproducer which is capable of relatively inexpensive manufacture on a quantity production basis by a series of steps which I have perfected.

Another object of my invention is to provide an arrangement of parts for electromagnetic sound reproducers which may be readily assembled by relatively unskilled labor for manufacturing sound reproducers on a large production scale.

Still another object of my invention is to provide a construction of base support for an electromagnetic sound reproducer having its several parts pressed from sheet metal in a succession of operations for developing and assembling the complete instrument from raw material within a relatively brief interval of time with a high degree of manufacturing efficiency.

Other and further objects of my invention will be pointed out in the specification hereinafter following by reference to the accompanying drawings, in which:

Figure 1 is an assembly view of the completed electromagnetic sound reproducer or table talker showing the assembly of the support of my invention; Fig. 2 is a plan view looking down upon the supporting base; Fig. 3 is a cross sectional view of the assembled base construction with the electromagnetic sound reproducer casing removed therefrom; Fig. 4 is a plan view looking upwardly below the base with the lower supporting member removed; Fig. 5 illustrates the top of the base member before the lip portions which form the gripping collar of the base about the side wall of the electromagnetic sound reproducer casing have been turned downwardly; Fig. 6 is a

perspective view of the gripping collar which is employed to draw the lips of the supporting flange of the base against the side walls of the electromagnetic sound reproducer; Fig. 7 is a view illustrating the assembly process of the complete parts of the support; and Fig. 8 is a view looking from beneath the assembled base partially broken away to show the interior of the support.

Heretofore in the art electromagnetic sound reproducers used in connection with radio receiving apparatus have been relatively expensive in construction due, among other things, to the failure of manufacturers to discover methods of manufacturing the parts of the reproducer associated with the electromagnetic mechanism in a systematic order, with parts so related that they might be readily assembled in producing the complete instrument.

I have developed a construction of support for an electromagnetic sound reproducer which may be produced by a succession of cutting and pressing operations with a molded cap member for the casing of the electromagnetic sound reproducer arranged for assembly with the pressed parts to produce an inexpensive and effective instrument.

One of the problems solved by my construction is the unitary assembly of the base and electromagnetic sound reproducer casing by means of molded projections on the cap which cooperate with apertures in the top base member to prevent relative rotation of the electromagnetic sound reproducer casing and the base.

Still another feature of my invention is the method by which I cover the lower base member with felt or cloth and at the same time secure necessary weight to the base of the instrument to position the center of gravity very near the supporting surface.

I accomplish this by a disk member having an upturned annular flange which fits snugly within the interior of the lower base member drawing the felt or cloth over the bottom and sides of the lower base member.

Another feature of the invention is the provision of depending lips or tongues on the top base member which may be drawn together by an annular collar to frictionally grip the walls of the electromagnetic sound reproducer casing, preventing the vertical withdrawal of the electromagnetic sound reproducer from the base at the same time

that the aforementioned projecting tongues on the cap preclude relative rotation of the cap and base.

Referring more particularly to the drawings, the assembled table talker is shown in Fig. 1 comprising an acoustic horn 1, a casing 2 for the electromagnetic sound reproducing mechanism, a cap 3 on the casing in which is secured a ferrule 4 and the 10 entire assembly supported in a base 5. The conductors leading to the electromagnetic operating mechanism pass into the base 5 through cable 6. The supporting base 5 comprises a plurality of parts including a 15 top portion 7 and a lower base portion 8. The base portion 8 and the top supporting base 7 are assembled, as more clearly shown in Fig. 3, wherein a layer of felt or other cloth 9 is rigidly drawn over the bottom and 20 sides of the base 9 by means of a disk insert 10 which is pressed into the interior of the base portion 8. The felt 9 on the exterior walls of the base portion 10 serves to frictionally bind the base portions 7 and 8 together 25 when the portion 8 is forced into the portion 7.

The base portion 7 is initially die pressed to the shape shown. The removal of the material in the center of the base 7 leaves a 30 plurality of tongues 14, 15, 16 and 17 protruding toward the center of the base portion 7 as illustrated more clearly in Fig. 5. The tongues are spaced apart by slots 18, 19, 20 and 21. The tongues 14, 15, 16 and 17 35 are pressed downwardly and at the same time an aperture 24 may be punched into base 7 to permit passage of the conductor 6 therethrough. The aperture 24 for the conductors is drawn inwardly, providing 40 round smooth edges to facilitate the passage of the conductors into the base. By a final operation on the base portion 7 a series of apertures 25 are punched in an annular ring about the flattened top of the base 7. These apertures are clearly illustrated in plan view in Figs. 2, 4, and 8.

The lower base member 8 is formed from flat sheet material by a pressing operation which provides an annular upstanding skirt 50 26 connected with a horizontal circular bottom plate depressed from the plane of the bottom of the member 8 as indicated at 27. The skirt 26 is then upset forming a shoulder 28 adjacent the plane of the bottom of the base member 8, completing the stamping and pressing operations upon this lower base member.

The insert member represented by reference character 10 is cut and pressed from sheet metal to the shape represented. The several parts are assembled together as represented in the drawings wherein the circular felt sheet 9 is stretched over the lower base member by the telescopically fitting insert 10 within the lower base member 8.

The felt lays smoothly over the annular shoulder 28 which forms a limiting stop when the upper base member 7 is telescopically fitted into the lower base member 8.

It will be understood that after completion of the cutting and pressing operations upon the base members that the material is subjected to heat treatment for ornamenting and beautifying the exterior surface appearance.

As represented more clearly in Fig. 7, the electromagnetic sound reproducing mechanism within the casing is provided with a molded cap 3 having depending projections 29 and 31. Still another projection 30 may be provided but is hidden from view in Fig. 7. These projections are spaced at intervals about the periphery of the lower edge of the skirt 32 of the cap 3 in proportion to the distances between the apertures 25 and the upper base member 7. When the instrument is to be assembled, these projections 29 and 31 enter corresponding apertures 25 and lock the electromagnetic mechanism against rotation with respect to the base. The cap 3 is thickened at its central portion 33 and threaded to receive the ferrule 4 serving as a seat and support for the acoustic horn 1. When the assembled table talker is inserted vertically downwardly into the supporting base and the projections 29 and 31 pass into apertures 25 locking the instrument against rotation with respect to the base, 1 clamp the casing 2 by frictional engagement with the depending lips 14, 15, 16 and 17 by means of a collar band 34 shown more clearly in Fig. 6. The band 34 is provided with a pair of interiorly directed projections 35 tending to bite into the casing 2 between a pair of the diametrically opposed slots 18, 19, 20 and 21. The collar 34 is drawn tightly against depending lips 14, 15, 16 and 17 by means of screw member 36. After the table talker has been firmly anchored against removal from the base member 7, the lower base member 8 is telescopically inserted within the upper base member 7 as heretofore described. The completed instrument is substantially sealed against tampering and requires no adjusting after passing a final and rigid factory inspection.

The metallic insert 10 serves not only as a means for stretching the felt 9 over the lower base member 8, but also as a weight to lower the center of gravity of the table talker. By this arrangement of telescopic members I avoid the necessity of gluing the felt to the base and secure a much more uniform product by reason of the tight stretching of the felt over the shoulder 28 which adds to the esthetic qualities of the instrument.

The construction of the support as hereinbefore described and the method of manu-

facturing the same has been found to be one of the practical embodiments of the invention, but it is to be understood that modifications may be made and that I intend no limitations upon the invention other than are imposed by the scope of the appended claims.

What I claim and desire to secure by Letters Patent of the United States is as follows:

1. A support for an electromagnetic sound reproducing mechanism, comprising in combination a casing including an electromagnetic operating mechanism, a cap secured to said casing, a plurality of depending projections on said cap, and a base provided with a plurality of apertures arranged to receive said projections when said casing is inserted in said base for locking said casing against relative rotation with respect to said base.
2. A support for an electromagnetic sound reproducer, comprising in combination a base member having a smaller diameter at its upper extremity than at its lower extremity, a casing containing an electromagnetic sound reproducing mechanism, and means in the upper extremity of said base member for securing said casing against withdrawal and relative rotation, consisting of a plurality of depending tongues, and means forcing said tongues into frictional engagement with said casing.

3. A support for an electromagnetic sound reproducing mechanism, comprising in combination an upper base member and a lower base member telescopically fitting together, a casing including an electromagnetic operating mechanism, means for securing said casing in said upper base member, comprising a plurality of downwardly extending tongues, and means for forcing said tongues in a substantially horizontal direction for frictionally engaging the walls of said casing consisting of a band adapted to have its ends drawn together for increasing the grip of said tongues upon said casing.

4. A support for an electromagnetic sound reproducer, comprising in combination a plurality of base members, including an upper base member and a pair of lower base members arranged to be telescopically secured together, one of said lower base members comprising a disk with an upwardly protruding annular flange thereon with an upset annular ring on said flange immediately adjacent the plane of said disk, said other base member comprising a disk of relatively smaller diameter with an upwardly extending flange for securing a layer of fabric over the first of said pair of base members and providing a mass for lowering the center of gravity of said electromagnetic sound reproducer.

DAVID H. MOSS.
